CONSTRUCTION OF SLIPS

Anna Friedman, New York, N. Y.

Application October 24, 1950, Serial No. 191,825

4 Claims. (Cl. 2—73)

1

This invention relates to undergarments and is particularly directed to women's slips or nightgowns.

It is an object of this invention to provide an undergarment of simple construction, economical to manufacture, at the same time to be form-fitting and to possess circumferential elasticity in all parts thereof.

Another object of my invention is to provide an undergarment constructed with the least possible amount of seams.

A further object of my invention is to provide a garment with a clinging effect.

Another object is to provide a garment which will not ride up or creep upwardly when the seat of the wearer in bent position expands, and will not burst at the sides of the hip portion.

Still a further object is to provide a garment of refined appearance which will retain the bust of the wearer and which will yieldably permit the wearer freedom of motion.

Still another object is to provide a garment of more durable construction with a body portion of a single blank of material.

Yet another object of this invention is to provide a garment which can be made in the form of either a slip, nightgown or dress, wherein only one vertical bias seam is provided for its body portion, and wherein the fitting qualities are improved, and wherein it greatly adds to the comfort of the wearer.

These and other advantages, capabilities and features will appear as the description proceeds. It will be evident that various details of its construction can be modified to a greater or lesser degree without departing from the principal features and the spirit of the present invention.

Other objects of this invention will in part be obvious and in part hereinafter pointed out.

The invention accordingly consists in the features of construction, combinations of elements, and arrangement of parts, which will be exemplified in the construction hereinafter described, and of which the scope of invention will be indicated in the following claims:

In the accompanying drawings in which is shown various illustrative embodiments of this invention,

Fig. 1 is a front perspective view of an undergarment embodying the invention, on a figure;

Fig. 2 is a rear perspective view thereof; and

Fig. 3 is a top plan view showing the pattern for the garment parts laid out on a piece of cloth for cutting.

I want it understood that I have made an at-

tempt in the drawings to show an actual style of a garment. My purpose herein is merely to illustrate a basic garment structure and to point out the distinguishing features thereof, so that persons skilled in the art can make the garment.

It will be apparent to such persons after reading this disclosure, how they can style and fit the garment in practically an unlimited variety of ways. The actual tailoring details are not part of the invention, as limited and defined in the claims.

Referring now in detail to the drawing, 10 designates an undergarment embodying the invention. The same comprises a high waisted body portion 11 and a brassière portion 12 at the upper end of the body portion. The brassière portion 12 comprises a front portion 13 and a rear portion 14 stitched together by a side seam 15. At the lower edge of the body portion 11 is a lace trim 16. At the upper ends of the front and back portions 13 and 14 of the brassière portion are front and rear lace trims 20 and 21 respectively, likewise stitched together by side seams 22. These lace portions 20 and 21 may be interconnected by shoulder strap portions 23.

Referring now to the body portion 11, it will be noted that the same is made of a single piece of textile material, the same being provided with a single seam 25 directly at the back. The front brassière portion 13 is stitched to the upper edge of the body portion by a seam 27 and the rear brassière portion 14 is stitched to the body portion 11 by a seam 28.

The pattern for the body portion 11 is shown in Fig. 3 of the drawing and is likewise designated by numeral 11. Said body portion 11 has a part-circular lower edge 30 and seam edges 31. The pattern 11 is symmetrical about its midsection. Its upper edge 33 is likewise symmetrical about its midpoint 34. Extending from the point 34 are upwardly curved portions 35 forming a V shaped notch 36 adjacent the point 34. Extending from the upwardly curved portions 35 are downwardly curved portions 37 from which extend outwardly and upwardly curved portions 39 extending to the upper ends 40 of the seam edges 31.

In Fig. 3 numeral 41 designates a piece of cloth from which the body 11 and brassière portions 13 and 14 are cut. Fig. 3 shows substantially the outlines of the patterns for pieces 11, 13 and 14 relative to the piece of cloth 41. Obviously in the piece of cloth 41 the weft and warp run transversely and longitudinally or lengthwise of the piece, respectively. The piece 11 as a

whole is laid out diagonally relative to the piece of cloth 41, whereby said piece is cut on the bias.

The piece 13 forming the front of the brassière portion has a lower edge 42 which is stitched to edges 35 of the piece 11. Thus the edge 42 has a central point 43 which registers with the point 34 of the piece 11. Extending to opposite sides of the point 43 are edge portions 44 which may be notched and gathered and stitched to said edges 35 thereby forming a fashioned bust receiving portion. At the outer ends of piece 13 are edges 45 which are stitched to the adjacent edges of the piece 14 to form the seams 15. Thus the central portion of the lower edge of the piece 13 fits within the notch 36 of the piece 11, as will be seen in the drawing.

At the upper edge of the piece 13 is a central point 47 from which extend upwardly and outwardly edges 48 forming points 49 from which extend downwardly inclined edges 50 extending to the end edges 45. Thus on either side of the central portion of piece 13 is formed a bust receiving cup.

As shown in Fig. 3 the piece 13 is laid on the piece of cloth 41, in a diagonal direction, so that said piece 13 is cut on the bias, whereby the bust cups will give or yield and conform to the wearer's bust.

Referring now to the piece 14, its position relative to the piece of cloth 41 is shown also. The piece 41 is likewise laid out in a diagonal direction so that said piece is cut on the bias. The piece 14 has at its lower edge a central point 51 which registers with the points 40 at the upper ends of the seam edges 31. Extending from the point 51 are upwardly and outwardly curved lower edges 52 which are stitched to the edges 39, 31 of the piece 11. At the ends of piece 14 are edges 55 which are stitched to the end edges 45 of piece 13 to constitute the seams 15. Thus the entire brassière portion is cut on the bias to make for comfortable wearing and for a good fit.

Due to the fact that the body portion 11 is also cut on the bias, a smoother fit is obtained and the skirt of the body will cling better to the body and will not creep up or ride up when the wearer bends or sits.

It will be noted that only a single seam is provided and this seam is more durable since the tension has been lessened by the bias throughout the garment.

The lace trim 16 at the bottom of the body 11 may be made to conform to the lower edge of the latter. It will be noted that the lace trim 20 for the front of the brassière comprises a pair of similar symmetrical front pieces 20a seamed together by a central seam 20b; extending to the point 47 of the piece 13. The lower edges of pieces 20a are stitched as by seams 20c to the edges 48 of the piece 13. These pieces 20a are inclined upwardly and outwardly as shown in Fig. 1 of the drawing. Their outer edges are seamed by seams 20d to a pair of similar symmetrically disposed downwardly and outwardly inclined lace pieces 20e which are seamed at their lower edges by seams 20f to the edges 50 of the piece 42. The end edges of lace pieces 20e are seamed to the back brassière portions 21 by means of said seams 22. The back lace portion 21 is stitched at its lower edge to the upper edge 14a of the piece 14 by a seam 21a.

It will now be understood that I have provided an undergarment of simple construction which is economical to manufacture and at the same time is form fitting and which is circumferen-

5 tially elastic and in which the body portion is provided with only a single seam at the back. It will now further be understood that the garment will have a clinging fit and will not ride up or creep up on the body of the wearer. Furthermore the brassière will yieldingly permit the wearer comfort of motion.

10 It will be further understood that the drawing is merely for the purpose of illustration and that various trim may be provided. It will be noted furthermore that the portion 11 is high waisted so that it comprises both a skirt portion and a waist portion and extends directly to the brassière portion of the garment.

15 Since side seams have been obviated in my new construction, the unsightly ridges having been eliminated, the slip hugs the body of the wearer so that the outer garments when worn with the slip hang properly and fit smoothly and enhance substantially the appearance of the wearer. By having the rear seam on the bias I eliminate any vertical straight portions in the garment and give thereby maximum stretchability to the garment.

20 It will thus be seen that there is provided a device in which the several objects of this invention are achieved and which is well adapted to meet the condition of practical use.

25 As various possible embodiments might be made of the above invention, and as various changes might be made in the embodiment above set forth, it is to be understood that all matter herein set forth or shown in the accompanying drawings is to be interpreted as illustrative and not in a limiting sense.

30 Having thus described my invention I claim as new and desire to secure by Letters Patent:

1. A combination slip and brassière garment consisting of a brassière comprising a front and a back brassière portions being made of cloth cut on the bias, the respective side edges of said front and back portions being joined together, the lower edges of said brassière front and back portions being located all around and just beneath the bust line of the wearer, and a close fitting princesse body member attached at its upper edges to the lower edges of said brassière member, said body member being made of a single blank of cloth, cut on the bias and having a single seam at the back of said body member, said back seam extending the full length of said body member, being smooth and unbroken throughout its length, said body member being formfitting and having no waist line, said body member extending from below the bust line of the wearer to a point below the knee and above the ankle of the wearer.

2. The combination of claim 1, the front brassière portion having downwardly extending V-shaped front central lower edge portion, said rear brassière portion having downwardly extending V-shaped portion at the center of its lower edge and said body member being formed at its upper edge with V-shaped cut-outs to receive the V-shaped portions of the front and rear brassière portion.

3. A combination slip and brassière garment consisting of a brassière comprising front and back brassière portions being made of cloth cut on the bias, the respective side edges of said front and back brassière portions being joined together, the lower edges of said brassière front and back portions being located all around and just beneath the bust line of the wearer, and a close fitting princesse body member attached at its upper edges to the lower edges of said brassière

sière member, said body member being made of a single blank of cloth cut on the bias and having a single seam at back of said body member, said back seam extending the full length of said body member, being smooth and unbroken throughout its length, said body member being formfitting and having no waist line, said body member extending from below the bust line of the wearer to a point below the knee, and having a ruffle attached to the lower edge of said body member.

4. The combination of claim 2, the front brassière portion having downwardly extending V-shaped front central lower edge portion, said rear brassière portion having a downwardly extending V-shaped portion at the center of its lower edge, and said body member being formed

at its upper edge with V-shaped cutouts to receive said V-shaped portions at the front and rear brassière portion.

ANNA FRIEDMAN.
